UNITED STATES PATENT OFFICE.

ALBERT E. RUETHER, OF ST. PAUL, MINNESOTA.

INTERNAL-COMBUSTION ENGINE.

1,268,056.

Specification of Letters Patent. Patented May 28, 1918.

Application filed April 24, 1917. Serial No. 164,214.

To all whom it may concern:

Be it known that I, ALBERT E. RUETHER, a citizen of the United States, residing at St. Paul, in the county of Ramsey and State of Minnesota, have invented new and useful Improvements in Internal-Combustion Engines, of which the following is a specification.

This invention relates to internal combustion engines of the four-cycle multiple cylinder double acting type. The invention relates more particularly to the means for controlling the admission of the explosive mixture to the combustion chambers of the cylinders and the exhaust of the burned gases therefrom.

One of the main objects of the invention is to provide a novel arrangement of ports and valves for the cylinders of the engine, there being one valve controlling the inlet and exhaust of one series of combustion chambers, and another valve controlling the inlet and exhaust of the other series of combustion chambers, and the intake and exhaust ports being so arranged with relation to the cylinders that said ports are intermittently covered and uncovered by the pistons, in addition to being closed and opened by the valves.

Another object of the invention is to so arrange the valves and the intake and exhaust ports that the valves are protected and shielded from the more intense heat which occurs immediately after ignition takes place, thereby preventing the valves from overheating.

Another object of the invention is to obtain greater power efficiency by providing against the loss of compression, such result being obtained by the means controlling the admission of the charges and the exhaust of the burned gases.

Another object in view is to provide a novel arrangement of multiple valve casing, enabling any particular valve port to be had access to without disturbing the remainder of the valve casing sections.

With the above and other objects in view, the invention consists in the novel construction, combination and arrangement of parts, herein fully described, illustrated and claimed.

In the accompanying drawings:—

Figure 1 is an end elevation of the improved engine.

Fig. 2 is a vertical transverse section through the same taken diametrically of one of the cylinders.

Fig. 3 is a fragmentary side elevation showing the manifold arrangement.

Fig. 4 is a fragmentary side elevation showing the sectional valve chamber arrangement.

Fig. 5 is a horizontal section in line with the axis of the upper valve.

Fig. 6 is an elevation of one valve seat.

The engine illustrated in the accompanying drawings is shown as of the four-cylinder, four-cycle type but it will of course be apparent that the engine may comprise any desired number of cylinders, two or more.

The cylinders are cast in block with separable heads also cast in block, 1 designating the block of cylinders, 2 the outer multiple cylinder head and 3 the inner multiple cylinder head, the battery or series of cylinders being thus formed in three pieces, the main cylinder block in which the combustion chambers are primarily open at both ends, and the outer and inner head blocks 2 and 3. 75 All of the members 1, 2 and 3 are water jacketed as indicated at 4, the jackets communicating with each other, the water being taken in at the inlet connection 4 and passing out at the outlet connection 5.

6 designates the crank case shown as divided at 7 into separable sections secured together by fastening means 8. 9 designates a bottom plate detachably secured to the crank case by fastening means 10. In each cylinder 2 is a double headed reciprocatory piston 11 carrying the usual packing rings 12 and having rigidly connected thereto a piston rod 13 which passes through a stuffing box or bushing 14 in the cylinder head 3 and carries at the crank case end a piston rod pin or journal 15 mounted in a cross head 16 which moves between cross head guides 17 interposed between the crank case and the cylinders. 18 designates the crank shaft 100 from which a connecting rod 19 extends to the respective cross head pin 15. The pistons 11 of all of the cylinders are connected to the common crank shaft 18.

Each cylinder is provided with two sets of 105 ports, there being one set for each combustion chamber 20 and 21 and each set comprising an intake port 22 and an exhaust port 23, both the intake port and the exhaust port of each set being controlled by a single valve 24 110

or 25 as the case may be. Each of the valves 24 and 25 extends along the whole series of cylinders and controls the intake and exhaust ports thereof. Each of said valves is cylindrical in shape and is cut away at suitable places as indicated at 26 to admit the charges to the intake ports and exhaust the burned gases from the cylinders. The intake and exhaust ports of each set are arranged side by side as indicated in Fig. 4 and are located at such a distance from the adjacent cylinder head that, both of said ports are covered by the respective piston 11 before it reaches the limit of its movement. The piston 15 is shown at one limit of its movement in Fig. 2 in which it will be seen that the lower head of the piston has moved considerably beyond the inner end of the port 22 or 23 as the case may be. Therefore both the 20 inlet and exhaust ports of the combustion chamber 21 are closed at such time. This serves to maintain the engine at a high working efficiency even though the valves 24 and 25 may have been subjected to wear and 25 would otherwise permit loss or leakage of compression. Furthermore, at the time when the valves would otherwise be subjected to the greatest heat, the intake and exhaust ports are closed by the piston 11 and the heat 30 cannot reach the valves until the piston has uncovered the intake and exhaust ports.

Each of the valves 24 and 25 is mounted in a bearing or bushing 27 of tubular formation, contained partly in a recess 28 of corresponding shape formed in the engine block 1, and partly in a sectional and divided part 29 of the valve casing. The part 29 is divided along the longitudinal and transverse lines 30 and 31 (see Fig. 4) into a plurality of rectangular plate-like sections 32 and these sections are secured to the engine block by bolts or cap screws 33 or the equivalent thereof. Some of these fasteners 33 are inserted through holes formed entirely in each 45 section 32, while others are inserted through holes formed in the meeting edges of the sections 32, such arrangement requiring a less number of bolts and therefore less work in removing any particular section 32 to get 50 access to the intake and exhaust ports. A considerable saving of time is thus effected when repair work and cleaning become necessary.

The valves 24 and 25 are provided with 55 extended shafts 34 and 35 which project beyond the end of the block of cylinders where they have fast thereon bevel gears 36 and 37 which mesh with other bevel gears 38 and 39 shown as fast on a common sleeve 40 secured by means 41 to a rotary valve actuating shaft 42 which extends in the direction of the crank case where it is provided with another bevel gear 43 meshing with a bevel gear 44 carried by a large gear 45 which 65 meshes with and is driven by a gear 46 on

the crank shaft 18, the gear 45 being twice the size of the gear 46 in order that the valves may be rotated at one-half the speed of the engine shaft, this being necessary to cause the engine to operate on the four-cycle principle. 70 The gears at the upper end of the shaft 42 are intended to be inclosed within a gear case 47, a similar or larger gear case 48 inclosing the gears 43, 44, 45 and 46 and also another gear 49 driven by the gear 45 and 75 intended to be used for driving a fan-belt pulley, a magneto, a generator, or any other device used in the engine equipment.

The pin 15 is formed with a central longitudinal bore 50 to receive oil from the crank case, the oil passage or bore 50 intersecting and communicating with another passage 51 extending centrally and longitudinally of the piston rod 13 and the piston 11 where it is intersected by radiating oil distributing 85 passages or ports 52 which lead outwardly to the periphery of the piston so as to furnish lubricating oil to the contacting surface of the piston and cylinder wall.

A single carbureter is intended to be used 90 in connection with the engine above described, said carbureter not being shown but being designed to be connected to an intake pipe 53 which leads to a manifold 54 the legs of which are formed with H-shaped extensions 55 the branches of which lead to the upper and lower sets of intake ports. Two exhaust manifolds 56 are employed for the two sets or series of exhaust ports and said exhaust manifolds will ordinarily be connected to a common exhaust pipe or a muffler as may be desired. 95

From the foregoing description taken in connection with the accompanying drawings it will now be seen that by the specified and 105 illustrated arrangement and location of the intake and exhaust ports of the cylinders, the valves are protected and prevented from overheating, because the ports controlled by said valves are covered by the piston during the initial portion of the firing stroke in each combustion chamber. On account 110 of this double closure for each of the intake and exhaust ports, loss of compression is prevented even though wear may have 115 taken place on the rotary valves or the bushings or bearings in which they turn. The result is that the power efficiency of the engine is maintained for a long period of time. Both cylinder heads are detachable from 120 the block of cylinders thus facilitating repair work and the removal of carbon. The gearing for transmitting motion to the valves is located exteriorly of the block of cylinders where it is easily and quickly accessible. 125

The construction of the engine as a whole is very simple and there are no delicate parts to get out of order, there being no cam shaft, push rods, push rod bushings, 130

springs and the like which are a constant source of trouble and require frequent attention.

I claim:—

- 5 1. In a multiple cylinder internal combustion engine, a block of cylinders, multiple cylinder heads detachably secured to said block of cylinders and forming combustion chambers at opposite sides of the pistons, 35
10 said cylinder block being formed with an intake port and an exhaust port for each combustion chamber arranged at such distances from the cylinder heads as to be covered and uncovered by the respective piston in each 40
15 complete back and forth movement thereof, rotary valves controlling said intake and exhaust ports and turning on parallel axes, said valves being geared to and positively driven from the crank shaft, a sectional 45
20 plate housing in said valves and divided along intersecting longitudinal and transverse lines into series of sections, each section having an intake port and an exhaust port in alinement with the respective intake 50
25 and exhaust ports in the cylinder walls, and means for fastening the sections of said plate in position enabling any section to be detached without disturbing the other sections, the valve driving means comprising 55
30 2. In a multiple cylinder internal combustion engine, a block of cylinders, multiple cylinder heads detachably secured to 60
said block of cylinders and forming combustion chambers at opposite sides of the pistons, said cylinder block being formed with an intake port and an exhaust port for each combustion chamber arranged at such distances from the cylinder heads as to be covered and uncovered by the respective piston in each complete back and forth movement thereof, rotary valves controlling said intake and exhaust ports and turning on parallel axes, said valves being geared to and positively driven from the crank shaft, a sectional plate housing in said valves and divided along intersecting longitudinal and transverse lines into series of sections, each section having an intake port and an exhaust port in alinement with the respective intake and exhaust ports in the cylinder walls, means for fastening the sections of said plate in position enabling any section to be detached without disturbing the other sections, the valve driving means comprising bevel gears fast on the shafts of said rotary valves, a countershaft perpendicular to the valve shafts and having reversely facing bevel gears thereon meshing with the bevel gears on the valve shafts, and motion transmitting means between the crank shaft and said countershaft.

In testimony whereof I affix my signature.

ALBERT E. RUETHER.
